Specification of Letters Patent.

Patented Nov. 2, 1915.

Application filed December 22, 1913. Serial No. 808,212.

To all whom it may concern:

Be it known that I, CHARLES A. KENWORTHY, a citizen of the United States, and a resident of the city of New York, county 5 of Bronx, and State of New York, have invented certain new and useful Improvements in Duplicators, of which the following is a specification.

The invention relates to duplicators of the 10 class having a duplicating medium of sufficient length to permit one working portion thereof to be shifted out of the way and a new working portion brought into operative position without stopping to remove the ink 15 from the section first used.

The invention has for one of its principal objects to provide an apparatus whereby the taking of impressions is facilitated by means of mechanism performing certain operations 20 which would otherwise have to be done by hand.

The invention consists in the novel construction, arrangement and combination of various elements, devices and parts as hereinafter more particularly described.

In the accompanying drawings Figure 1 is a front view of my invention, Fig. 2 is a side view of the same, Fig. 3 is a transverse vertical section taken on the line 3—3 of 30 Fig. 1, Fig. 4 is a longitudinal section of one of the rollers carrying the duplicating surface, Figs. 5, 6, 7, 8, 9 and 10 are enlarged detailed views, and Fig. 11 is a sectional view of a modified form of the paper 35 guiding devices all as hereinafter more particularly described.

In carrying my invention into effect in the embodiment thereof which I have selected for illustration in the accompanying 40 drawings and description in this specification, I provide a base 14, having uprights 15 and 16 rigidly secured at the sides thereof.

Supported in the upright 16, and rigidly secured thereto by the set-screw 17, is one 45 end of a rod 18, said rod extending the width of the machine. The other end of the rod 18 is supported by the upright 15 in a manner hereinafter to be described. Rigidly mounted on this rod 18 is a stationary 50 frame, having the form of a skeleton cylinder, comprising end pieces 19, and a sheet of metal 20 substantially semicircular in cross-section (best shown in Fig. 3).

The duplicating sheet 21 is stored on the

roller 22. The portion in use is unwound 55 from this roller and passed around outside the metal surface 20, this part of the sheet being designated 23 (see Fig. 2.) After the sheet has been used it is wound upon the roller 24. These rollers may be of any convenient form and may be connected to the remainder of the machine and operated when therein by any suitable mechanism. In the accompanying drawings I have shown a form of such rollers and of connecting and 60 operating means which I will now describe. Referring more particularly to Fig. 4 the roller will be seen, marked there 22, but it will be understood that the roller 24 may be similarly constructed. Projecting from the 65 center of each end of the roller is a pin 25, and from near the edge of each end two shorter pins 26. Journaled in one of the members 19 is a rotatable member 27, having at its outer end a transverse bar 28 by which 70 it may be rotated, and on the inner portion a ratchet 29 adapted to engage with a pawl 30. The pawl and ratchet is shown enlarged in Fig. 5. The center of the inner end of the member 27 is provided with a socket 75 adapted to receive one of the pins 25 on the roller 22, and two grooves are also provided at the sides of the member 27 to receive the pins 26. Thus the roller 22 may be rotated by turning the member 27, and it is held 80 against backward rotation by the pawl and ratchet 30 and 29. In the other member 19 is secured a socket, the detailed construction 85 of which is shown more particularly in Fig. 6. The socket consists of a fixed member 90 32 having a semi-circular bearing, and rigidly secured to the member 19, and a lever 33, pivoted to the member 19 at 34, and held in contact with the member 32 by means of the spring 35. This lever 33 also contains a 95 semi-circular bearing similar to that of the member 32. When the members are in contact the two semi-circular bearings form a journal for the pin 25, and when the lever 33 is pressed away from the member 32 the 100 roller 22 may be lifted from the bearings.

Rotatably mounted on the shaft 18 between one of the members 19 and the support 16, is a sleeve 40 having secured thereto arms 41 and 45. Journaled in the support 105 15 is a shaft 42, to the outer end of which is rigidly secured a crank 43. At the inner end of the shaft 42 is a recess adapted to

receive one end of the shaft 18. (The construction is shown by the dotted lines in Fig. 1.) Mounted on the shaft 42, and secured to the same so as to rotate therewith and between the member 19 and the support 15, is a sleeve 44 provided with arms 46 and 47, this construction being similar to the sleeve 40 with its arms 41 and 45. The outer end of the arm 47 and of the arm 45 are rigidly secured to a cross-bar 50. Similarly the ends of the arms 41 and 46 are rigidly secured to a cross-bar 51. The effect of this construction is to produce a rigid rectilinear frame, the ends thereof being formed of the arms 41, 45, 46 and 47 and the sides being formed of the cross-bars 50 and 51, the said frame being mounted on the shaft 18 in such a manner as to be exterior to the stationary cylindrical frame and to permit of the former being rotated by means of the crank 43.

Journalled in the ends of the arms 45 and 47 and parallel with the cross-bar 50 is a roller 52, adapted to be yieldingly pressed by the springs 152 so as to bear against the surface 23 when the movable frame is rotated. Rigidly mounted on the arm 47, near its end, is a shoe 53, the use of which will be hereafter explained.

Similarly journalled in the ends of the arms 41 and 46 is a roller 62, and in extensions of said arms is journalled a roller 63. These two rollers are geared together at one end, and indicated by 66 (Fig. 1) and the roller 62 is geared by means of the gear-wheel 64 to a circular rack 65 on the stationary frame. These rollers do not touch the stationary frame, but when the movable frame is rotated the rollers are also rotated by means of the gear 64 meshing with the rack 65 and the gears 66 meshing with each other. Mounted on the cross-bar 51 is a metal guide 67, (shown in Fig. 3) and mounted on the outer ends of the arms 41 and 46 is another metal guide 68. This guide 68 is adjusted so as to barely clear the stationary frame. Mounted on the outer end of the arm 41 is a roller 70, the purpose of which will be hereinafter set forth.

Rotatably and slidably mounted in a perforation in one of the members 19 is a plug 100, held normally in its inner position by a helical spring 101. Located in the inner end of this plug 100 is a square socket adapted to receive one end 102 of a square shaft 71, whose other end 103 is received by a square socket in the inner end of a pin 104 which is rotatably mounted in the other member 19. (This construction is best shown in Figs. 7, 8, 9 and 10.)

Rigidly secured to the square shaft 71 is a metal guide 72. On the outer end of the pin 104 is rigidly mounted a cam 73, (see Figs. 9 and 10). Pivoted to one of the members 19 is a lever 74 provided with a later-

ally extending pin 75. When the movable frame is rotated this lever is depressed by the roller 70, and in turn depresses the cam 73 by means of the pin 75, thus partially rotating the shaft 71 and raising the outer edge of the guide 72.

Rotatably mounted in brackets on the square shaft 71 and parallel to said shaft 71, is another square shaft 76. On this shaft is rigidly mounted a cam 77. On the outside of the said member 19 is pivoted a lever 78, one end thereof being adapted to be moved by the shoe 53, and the other end being provided with a laterally extending pin 179, which is adapted to engage with the cam 77 and thus partially rotate the shaft 76. Mounted on the shaft 76 are fingers 79 which are adapted when the shaft 76 is partially rotated, to bear against the metal guide 72.

Rigidly secured to the support 15 and 16 are two supporting arms 80. Attached to these supporting arms 80 is an inclined shelf 81 having its length adjustable by means of the set-screw 82. At the top of this inclined shelf is a horizontal shelf 83 adapted to hold the paper 84 which is used in the machine.

Fig. 11 shows a modified form of the devices for removing the paper from the machine after it has been printed upon. In this form the rollers 62 and 63 are mounted in the manner heretofore described, but instead of the guide 68 a modified form of guide is employed. This modified form is designated 168 and is of a double-curved or sigmoid form as shown. This form of guide is better adapted under some circumstances for the purpose of guiding between the rollers 62 and 63 the paper in the duplicating machine, as will be hereinafter fully described.

The operation of my invention is as follows: The shaft 71 and the mechanism mounted thereon are removed from the machine by pulling out the plug 100 against the tension of the spring 101, which action enables the shaft 71 to be lifted out of its bearings. The end of the duplicating sheet 21, which is wound upon the roller 22, is then passed around outside the sheet metal member 20, as shown at 23 in Figs. 2 and 3, and attached to the roller 24, around which it is given a few turns. The surface 23 is drawn taut by means of the ratchet wheels 29. The surface 23 is the part of the sheet 115 from which the impressions are taken. The impression is transferred thereto from the original by placing the original thereon, and passing the roller 52 thereover by rotating the crank 43 and said original is then 120 removed. After having placed the duplicating sheet in the machine, and having transferred thereto an impression from the original of which it is desired to make copies, the procedure is as follows: A sheet of paper 125

or the like on which the copies are to be made is taken from the pile 84 on the horizontal shelf 83 and laid on the sloping shelf 81, its lower portion resting on the metal guide 72. The crank 43 should be in such a position that the roller 52 will be toward the front of the machine, and the roller 62 toward the rear. The crank 43 is then rotated in a counter-clockwise direction. As the roller 52 reaches the top of the machine the shoe 53 comes in contact with the lever 78, moving the upper end of the same backward, and thus moving the pin 179 forward. The pin 179 presses against the lever 77, thus rotating the shaft 76 and causing the fingers 79 to be depressed upon the guide 72, securely clamping in position the sheet of paper thereon. As the crank 43 is further rotated, the roller 52 passes over the paper, (which is shown in Fig. 3 by the dotted line 85) drawing the upper portion through the space between the top of the machine and the lower edge of the sloping shelf 81, and pressing the said paper into contact with the duplicating surface at 23, thus transferring an impression from the surface to the paper. As the crank 43 is still further rotated, the roller 70 passes over the lever 74, depressing it. As the lever 74 is depressed the pin 75 in turn depresses the cam 73 thus partially rotating the shaft 71 and raising the edge of the metal guide 72. As the guide falls again after the roller 70 has passed completely over the lever 74, the fingers 79 are left in the position shown in Fig. 7 and no longer clamp the paper to the guide 72. The edge of the paper is also raised and no longer rests against the square shaft 71. As the paper has a tendency to stick to the duplicating surface, however, it still remains in place except for the raising of the edge. As the crank 43 is still further rotated the machine comes into position shown in the accompanying drawings with the roller 62 at the top. The raised edge of the paper is caught by the guide 68, and thus passed between the fingers 63 and 62, as best shown in Fig. 11. If the paper should be made to pass too high, it would be in Fig. 11 the guide 67. When the form shown in Fig. 11 is used, the paper is lifted by the guide 105 as will be obvious from what has been already explained. The paper can then be completely separated from the duplicating surface by further rotating the crank 43 the entire sheet passing between the rollers 61 and 62 and falling into a tray or other receptacle provided therefor. The process may be repeated as many times as desired.

When all the impressions which are desired to be taken from the original have been completed and it is desired to take impressions from a new original, a fresh or new face may be brought into play by dis-

engaging the pawls 30 from the ratchets 29, and rotating the keys 28 of the rollers 22 and 24.

When the entire sheet of duplicating medium has been used the rollers 22 and 24 may be rotated in the reverse direction, so as to successively bring different parts of the medium again into operation. As the ink sinks into the duplicating medium and becomes inoperative, the same sheet may be used repeatedly.

The advantages of my invention will be obvious. Instead of the operations which have heretofore been necessary, the user of my invention needs but to perform two operations; namely, placing the paper on the sloping shelf and rotating the crank. These operations may be performed much more quickly than any of the hand operations, and it is therefore possible by my method to take impressions with great ease and rapidity.

Having thus described my invention what I claim as new and desire to secure by Letters Patent is as follows.

1. In a duplicator, the combination with a stationary frame adapted to support a duplicating medium, of a rotary frame provided with a plurality of rollers adapted to bring paper or the like in contact with said medium while an impression is transferred from said medium to said paper, and then to remove said paper from contact with said medium.

2. In a duplicator, the combination with a stationary frame, of a roller attached thereto and adapted to bear a roll of duplicating medium to be unwound therefrom, the roller comprising a portion of said duplicating pressure for use, a second roller on which said medium may be wound, and a rotary frame provided with a plurality of rollers, one of said rollers being adapted to bring paper or the like in contact with the duplicating medium.

3. In a duplicator, the combination with a stationary frame, of a roller attached thereto and bearing a roll of duplicating medium, the roller comprising a portion of said duplicating medium for use, a second roller on which said duplicating medium is wound, and a rotary frame provided with a plurality of rollers, one of which is journaled to the rear of the frame and adapted to bring paper or the like in contact with said duplicating medium, when an impression is transferred from said paper to said duplicating medium to remove said paper from contact with said medium.

4. In a duplicator, the combination with a stationary frame adapted to support a duplicating medium, of a roller provided with a journal bearing, a roller adapted to bring paper or the like in contact with said duplicating medium when an impression is transferred from said paper to said duplicating medium.

and then to remove said paper from contact with said medium, and devices adapted to clamp the said paper.

5. In a duplicator, the combination with a stationary frame, of a roller attached thereto containing a roll of duplicating medium, means for exposing a portion of said duplicating medium for use, a second roller on which said medium may be stored after use, 10 and a rotary frame provided with a plurality of rollers, one of said rollers being adapted to bring paper or the like in contact with said duplicating medium, and devices adapted to clamp said paper.

15 6. In a duplicator, the combination with a stationary frame, of a roller attached thereto containing a roll of duplicating medium, means for exposing a portion of said duplicating medium for use, a second roller on 20 which said duplicating medium may be stored, a rotary frame provided with a plurality of rollers adapted to bring paper or the like in contact with said duplicating medium while an impression is transferred 25 from said medium to said paper, and then to remove said paper from contact with said medium, and devices adapted to clamp the said paper.

7. In a duplicator, the combination with a stationary frame adapted to support a duplicating medium, of a rotary frame adapted to bring paper or the like in contact with said duplicating medium, and devices on said stationary frame adapted to raise an 35 edge of said paper.

8. In a duplicator, the combination with a stationary frame adapted to support a duplicating medium, of a rotary frame adapted to bring paper or the like in contact with said duplicating medium while an impression is transferred from said medium to said paper, and to remove said paper from contact with said medium, and devices on said stationary device adapted to elevate 45 an edge of said paper after it has received said impression.

9. In a duplicator, the combination with a stationary frame, of a roller attached thereto containing a roll of duplicating medium, means for exposing a portion of said duplicating medium for use, a second roller on which said medium may be stored after use, a rotary frame adapted to bring paper or the like in contact with said duplicating 55 medium, and devices on said stationary frame adapted to elevate an edge of the said paper.

10. In a duplicator, the combination with a stationary frame, of a roller attached thereto containing a roll of duplicating medium, means for exposing a portion of said duplicating medium for use, a second roller on which said duplicating medium may be stored after use, a rotary frame adapted to 60 bring paper or the like in contact with said

duplicating medium while an impression is transferred from said medium to said paper, and to remove said paper from contact with said medium, and devices adapted to elevate an edge of the said paper.

70 11. In a duplicator, the combination with a stationary frame adapted to support a duplicating medium, of a rotary frame adapted to bring paper or the like in contact with said duplicating medium, and devices adapted to clamp the said paper; said devices comprising a shaft mounted on said stationary frame, a sheet of metal attached to said shaft, a second shaft mounted on said stationary frame, a finger mounted on said second named shaft adapted to bear against the sheet of metal on the first mentioned shaft when the second named shaft is rotated, a cam mounted on said second named shaft, a lever mounted on said stationary frame, said lever carrying a pin adapted to move said cam, and a shoe carried by said rotary frame adapted to move said lever.

80 12. In a duplicator, the combination with a stationary frame adapted to support a duplicating medium, of a rotary frame adapted to bring paper or the like in contact with said duplicating medium while an impression is transferred from 90 said medium to said paper, and to remove said paper from contact with said medium, and devices adapted to clamp the said paper; said devices comprising a shaft mounted on said stationary frame, a sheet of metal attached to said shaft, a second shaft mounted on said stationary frame, a finger mounted on said second named shaft adapted to bear against the sheet of metal on the first mentioned shaft when the second named shaft is rotated, a cam mounted on said second named shaft, a lever mounted on said stationary frame, said lever carrying a pin adapted to move said cam, and a shoe carried by said rotary frame adapted to 100 move said lever.

95 13. In a duplicator, the combination with a stationary frame, of a roller attached thereto adapted to support a duplicating medium, means for exposing a portion of said duplicating medium for use, a second roller on which said medium may be stored after use, a rotary frame adapted to bring paper or the like in contact with said duplicating medium, and devices adapted to 115 clamp the said paper; said devices comprising a shaft mounted on said stationary frame, a sheet of metal attached to said shaft, a second shaft mounted on said stationary frame, a finger mounted on said second named shaft adapted to bear against the sheet of metal on the first mentioned shaft when the second named shaft is rotated, a cam mounted on said second named shaft, a lever mounted on said stationary frame, said lever carrying a pin adapted to move said cam, and a shoe carried by said rotary frame adapted to 120 move said lever.

125 14. In a duplicator, the combination with a stationary frame, of a roller attached thereto containing a roll of duplicating medium, means for exposing a portion of said duplicating medium for use, a second roller on which said medium may be stored after use, a rotary frame adapted to bring paper or the like in contact with said duplicating medium, and devices adapted to 130 clamp the said paper; said devices comprising a shaft mounted on said stationary frame, a sheet of metal attached to said shaft, a second shaft mounted on said stationary frame, a finger mounted on said second named shaft adapted to bear against the sheet of metal on the first mentioned shaft when the second named shaft is rotated, a cam mounted on said second named shaft, a lever mounted on said stationary frame, said lever carrying a pin adapted to move said cam, and a shoe carried by said rotary frame adapted to move said lever.

frame, said lever carrying a pin adapted to move said cam, and a shoe carried by said rotary frame adapted to move said lever.

14. In a duplicator, the combination with 5 a stationary frame, of a roller attached thereto adapted to support a duplicating medium, means for exposing a portion of said duplicating medium for use, a second roller on which said duplicating medium 10 may be stored after use, a rotary frame adapted to bring paper or the like in contact with said duplicating medium while an impression is transferred from said medium to said paper, and to remove said paper 15 from contact with said medium, and means for clamping said paper; said means comprising a shaft mounted on said stationary frame, a sheet of metal attached to said shaft, a second shaft mounted on said stationary frame, a finger mounted on said second named shaft adapted to bear against the sheet of metal on the first mentioned shaft when the second named shaft is rotated, a cam mounted on said second named 20 shaft, a lever mounted on said stationary frame, said lever carrying a pin adapted to move said cam, and a shoe carried by said rotary frame adapted to move said lever.
15. In a duplicator, the combination with 30 a stationary frame adapted to support a duplicating medium, of a rotary frame adapted to bring paper or the like in contact with said duplicating medium, and devices adapted to elevate the edge of the said paper; said devices comprising a shaft mounted on said stationary frame, a sheet of metal mounted on said shaft, a cam mounted on said shaft, a lever mounted on said stationary frame, and provided with a pin adapted 35 to depress the said cam, and a roller mounted on said rotary frame adapted to depress the said lever.
16. In a duplicator, the combination with 45 a stationary frame adapted to support a duplicating medium, of a rotary frame adapted to bring paper or the like in contact with said duplicating medium while an impression is transferred from said medium to said paper, and to remove said paper 50 from contact with said medium, and devices adapted to elevate an edge of the said paper; said devices comprising a shaft mounted on said stationary frame, a sheet of metal mounted on said shaft, a cam mounted on said shaft, a lever mounted on said stationary frame, and provided with a pin adapted 55 to depress the said cam, and a roller mounted on said rotary frame adapted to depress the said lever.
17. In a duplicator, the combination with 60 a stationary frame, of a roller attached thereto and adapted to support a duplicating medium, means for exposing a portion of said duplicating medium for use, a second roller on which said duplicating medium 65
14. In a duplicator, the combination with 5 a stationary frame, of a roller attached thereto adapted to support a duplicating medium, and devices adapted to elevate an edge of the said paper; said devices comprising a shaft mounted on said stationary frame, a sheet of metal mounted on said shaft, a cam mounted on said shaft, a lever mounted on said stationary frame, and provided with a pin adapted to depress the said cam, and a roller mounted on said rotary frame adapted to depress the said lever.
18. In a duplicator, the combination with 10 a stationary frame, of a roller attached thereto and adapted to support a duplicating medium, means for exposing a portion of said duplicating medium for use, a second roller on which said duplicating medium may be stored after use, a rotary frame adapted to bring paper or the like in contact with said duplicating medium while an impression is transferred from said medium to said paper, and to remove said paper 15 from contact with said medium, and devices adapted to elevate an edge of said paper; said devices comprising a shaft mounted on said stationary frame, a sheet of metal mounted on said shaft, a cam mounted on said shaft, a lever mounted on said stationary frame, and provided with a pin 20 adapted to depress the said cam, and a roller mounted on said rotary frame adapted to depress the said lever.
19. In a duplicator, the combination with 25 a stationary frame adapted to support a duplicating medium, of a rotary frame provided with a plurality of rollers, and devices coöperating with one of said rollers, said roller and said coöperating devices being adapted to bring paper or the like in contact with said duplicating medium.
20. In a duplicator, the combination with 30 a stationary frame adapted to support a duplicating medium, of a rotary frame provided with a plurality of rollers, and devices coöperating with said rollers, said rollers and said coöperating devices being adapted to bring paper or the like in contact with said duplicating medium while an impression is transferred from said medium to said paper, and then to remove said paper from contact with said duplicating medium.
21. In a duplicator, the combination with 35 a stationary frame, of a roller attached thereto and adapted to support a duplicating medium, means for exposing a portion of said duplicating medium for use, a second roller on which said duplicating medium may be stored after use, and a rotary frame provided with a plurality of rollers, and devices coöperating with one of said rollers, said roller and said coöperating devices being adapted to bring paper or the like in contact with said duplicating medium.
22. In a duplicator, the combination with 40 a stationary frame, of a roller attached thereto and adapted to support a duplicating medium, means for exposing a portion of said duplicating medium for use, a second roller on which said duplicating medium

a stationary frame, of a roller attached thereto and adapted to support a duplicating medium, means for exposing a portion of said duplicating medium for use, a second roller on which said duplicating medium may be stored after use, and a rotary frame provided with a plurality of rollers, and devices coöperating with said rollers, said rollers and said coöperating devices being adapted to bring paper or the like in contact with said duplicating medium while an impression is transferred from said medium to said paper, and then to remove said paper from contact with said medium.

23. In a duplicator, the combination with a stationary frame adapted to support a duplicating medium, of a rotary frame bearing devices adapted to bring paper or the like in contact with said duplicating medium while an impression is transferred from said medium to said paper, and devices adapted to remove said paper from contact with said medium; said removing devices comprising a pair of rollers between which the paper is adapted to pass and a guide adapted to lead said paper between the said rollers.

24. In a duplicator, the combination with a stationary frame, of a roller attached thereto adapted to support a duplicating medium, means adapted to expose a portion of said duplicating medium for use, a second roller on which said duplicating medium may be stored after use, and a rotary frame bearing devices adapted to bring paper or the like in contact with said duplicating medium while an impression is transferred from said medium to said paper, and devices adapted to remove said paper from contact with said medium; said removing

devices comprising a pair of rollers between which the said paper is adapted to pass, and a guide adapted to lead said paper between the said rollers.

25. A duplicator comprising a stationary frame and a rotary frame, and provided with devices whereby paper may be removed from the same, said devices comprising a pair of rollers between which the paper is adapted to pass, and means mounted on said stationary frame adapted to elevate an edge of the said paper. 45

26. A duplicator comprising a stationary frame and a rotary frame, and provided with devices whereby paper may be removed from the same, said devices comprising a pair of rollers between which the paper is adapted to pass, means mounted on said stationary frame and adapted to elevate an edge of the said paper, and a guide 50 adapted to feed an edge of the paper between the said rollers. 55

27. A duplicator comprising a stationary frame and a rotary frame, and provided with devices whereby paper may be removed from the same, said devices comprising a pair of rollers between which the paper is adapted to pass, means mounted on said stationary frame and adapted to elevate an edge of the said paper, and a guide having 60 a double-curved form adapted to feed an edge of the paper between the said rollers. 65

In witness whereof I have hereunto signed my name this 20th day of December, 1913, in the presence of two subscribing witnesses. 70 75
